UNITED STATES PATENT OFFICE.

JAMES J. TRACY, OF CLEVELAND, OHIO.

ADJUSTABLE HEAD-LAMP BRACKET.

1,304,827.

Specification of Letters Patent. Patented May 27, 1919.

Application filed October 28, 1914. Serial No. 868,974.

To all whom it may concern:

Be it known that I, JAMES J. TRACY, a citizen of the United States, and a resident of Cleveland, county of Cuyahoga, and State of Ohio, have invented a new and useful Improvement in Adjustable Head-Lamp Brackets, of which the following is a specification, the principle of the invention being herein explained and the best mode in which I have 10 contemplated applying that principle, so as to distinguish it from other inventions.

The present invention has for its object the provision of an auxiliary adjustable lamp bracket to be used with the present bracket and lamp, to allow the lamp to be adjusted up and down in a vertical plane. The present brackets hold the lamp so that the beam of light is projected forward in substantially a horizontal plane and one of the objects of the present supplemental bracket is to allow the lamps to be tilted forward to concentrate the light on the road, a short distance ahead of the automobile, so that the lamps may not throw a glaring light ahead. The present bracket allows this to be done, and also permits the lamps to be brought back to a substantially horizontal position for country driving. "Dimmers" of various kinds have been tried, but the present device does away 30 with the necessity of using dimmers, and is found to satisfy the ordinances against glaring headlights. To the accomplishment of the foregoing and related ends, said invention, then, consists of the means hereinafter 35 fully described and particularly pointed out in the claims.

The annexed drawing and the following description set forth in detail certain mechanism embodying the invention, such description 40 means constituting, however, but one of various mechanical forms in which the principle of the invention may be used.

In said annexed drawing:

Figure 1 is a perspective of the bracket showing the same in use with a lamp; Fig. 2 is a side elevation of the device; Fig. 3 is a section on line 3—3, Fig. 2; Fig. 4 is a section on the line 4—4, Fig. 2 and Fig. 5 is a side elevation partly in section showing a different form of lamp carrying pin. The ordinary U-shaped lamp bracket 1 is shown, over the arm 2 of which, is fastened the horizontal arm 3 of the auxiliary bracket by means of a clamping bolt or clip 4 and nuts 5. This arm 3 extends forward substantially horizontal, and at its forward end is

provided with a preferably conical recess 6, and a hole 7 is drilled from the apex of the recess through the arm. A lug 8 is formed on the face of the arm adjacent the recess. 60

A second or lamp-carrying arm 9 has a conical projection 10 which is adapted to fit within the recess 6 of the horizontal arm. Through the arm and projection a hole 11 is formed so that when the two arms are fitted 65 together, the holes are alined. In the side of the second arm a preferably square recess 12 is cut around the hole. Into this recess the head 13 of the clamping bolt 14 fits snugly so that the bolt may not turn without moving the arm 9. At the base of the second arm a second lug 15 is formed, which is tapped and has a cap screw 16 extending therethrough. A lock nut 25 is provided in order to retain the cap screw in any desired 70 position. In order to provide a fixed stop to determine the vertical position of the arm 9, a shoulder 23 is formed integral with said arm, which contacts with the side of lug 8 to limit further movement of arm 9. 80

The upper portion 17 of the second arm is made in the form of a pin which is adapted to be inserted in the aperture 18 on the projecting ear 19 of the usual lamp. This pin is formed with a tapered base 20, and is 85 threaded at its upper end. A nut 21 with a wedge-shaped portion 22 is adapted to screw on to the tapered part of the pin to hold the lamp firmly in place.

When two of these auxiliary lamp brackets are employed and the lamp is pinned thereon, it is adjusted in a vertical plane until the light is projected in front of the car to whatever distance may be prescribed in the ordinance. The castle nut 26 on bolt 14 is then pulled as tightly as is possible and yet allow the lamps to be moved by hand, after which the set screw 16 is adjusted to contact with the lug 8 and is then locked. This, of course, limits the angle of the lamp 100 and need only be adjusted once. If, as often happens, it is desirable to throw the light ahead in a substantially horizontal plane, it is necessary only, to push the lamps to this position which is determined by the fixed 105 stop. The faces of the conical projection and recess provide sufficient friction so that the lamps will stay in either this upright position or in the inclined position or for that matter in any intermediate position. 110

It will be seen from the foregoing, that several advantageous features are incorpo-

rated in the present device. It allows the lamp to be adjusted to throw the light at any desired angle which can be determined and can be fixed. It also allows the lamps to be set horizontally for country driving with the necessity of simply moving them to the desired position as determined by a fixed stop no tightening of nuts being required. The tapered base of the pin and the tapered nut wedge the lamp tightly upon the pin or the usual straight pin on the bracket and set screw on the lamp may be employed, as shown in Fig. 5.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a vehicle lamp support, the combination of an arm provided at one end with a cone-shaped recess; a second arm adapted to support a lamp and provided with a complementary projection adapted to fit within such recess; means for clamping said two arms together; fixed stop means on said arms adapted to limit angular movement of the same to prevent the lamp from being tilted above the horizontal; and adjustable stop means adapted to limit the angular movement of said arms in the other direction.

2. In an auxiliary lamp-bracket, the combination of an arm provided at one end with means adapted to secure the same to a lamp-bracket pin, said arm being provided at the other end with a cone-shaped recess; a second arm adapted to support a lamp and provided with a complementary projection adapted to fit within such recess; means for clamping said two arms together; fixed stop means adapted to positively limit the angular movement between said arms in one direction; and adjustable stop means adapted to similarly limit such movement in the opposite direction.

3. In an auxiliary lamp-bracket the combination of an arm provided at one end with a clamping member adapted to secure the same about a lamp-bracket pin, said arm being provided at the other end with a cone-shaped recess and having an opening through said arm from the apex of such recess; a second arm adapted to be received in the aperture in the ear of a lamp, said second arm being adapted to support a lamp and provided with a conical projection adapted to fit within such recess and having an opening through said arm and said projection, such opening being alined with such opening in said first-named arm; a clamping bolt passing through such open-

ings in said arms and adapted to hold said arms firmly together; means adapted to prevent rotation of said bolt with respect to said second arm; and fixed stop means adapted to positively limit the angular movement between said arms in one direction; and adjustable stop means adapted to similarly limit such movement in the opposite direction.

4. In an auxiliary lamp-bracket, the combination of an arm provided at one end with a clamping member adapted to be clamped about a lamp bracket pin, said arm being provided at the other end with a conical shaped recess and having an opening through said arm from the apex of such recess; a second arm adapted to be received in the aperture in the ear of a lamp, said second arm being adapted to support a lamp and provided with a conical projection adapted to fit within such recess and having an opening through said arm and said projection, such opening being alined with such opening in said first-named arm; a clamping bolt passing through such openings in said arms and adapted to hold said arms firmly together, said second arm being provided with a polygonal recess and the head of said clamping bolt being adapted to fit snugly therein to prevent rotation of said arm with respect to said bolt; a lug on said first-named arm; a second lug on said second arm, said two lugs being adapted to contact upon movement of one arm relative to the other and thereby positively limit the angular movement between said arms in one direction; and a set screw mounted in said second arm and adapted to contact with the lug on said first arm to adjustably limit the movement between said arms in the opposite direction.

5. A lamp-bracket comprising an arm provided with a cone-shaped recess and having an opening through said arm from the apex of such recess; a second arm adapted to be received in the aperture in the ear of a lamp, said second arm being adapted to support a lamp and provided with a conical projection adapted to fit within such recess and having an opening through said arm and said projection, such opening being alined with such opening in said first-named arm; a clamping bolt passing through such openings in said arms and adapted to hold said arms firmly together; means adapted to prevent rotation of said bolt with respect to said second arm; stop means adapted to positively limit the angular movement between said arms in one direction; and adjustable stop means adapted to similarly limit such movement in the opposite direction.

6. A lamp-bracket comprising an arm provided with a cone-shaped recess and having an opening through said arm from

apex of such recess; a second arm adapted to be received in the aperture in the ear of a lamp, said second arm being adapted to support a lamp and provided with a conical projection adapted to fit within such recess and having an opening through said arm and said projection, such opening being aligned with such opening in said first-named arm; a clamping bolt passing through such openings in said arms and adapted to hold said arms firmly together, said second arm being provided with a polygonal recess and the head of said clamping bolt being adapted to fit snugly therein to prevent rotation of said arm with respect to said bolt; a lug on said first-named arm; a second lug on said second arm, said two lugs being adapted to contact upon movement of one arm relative to the other and thereby positively limit the angular movement between said arms in one direction; and a set screw mounted in said second arm and adapted to contact with the lug on said first arm to adjustably limit the movement between said arms in the opposite direction.

Signed by me this 22d day of October, 1914.

JAMES J. TRACY.
